Patented Dec. 15, 1925.

1,566,019

UNITED STATES PATENT OFFICE.

ERWIN JOSEPHY, OF NEW YORK, N. Y.

COMBINED MENU CARD AND BILL.

Original application filed April 29, 1921, Serial No. 465,385. Divided and this application filed March 13, 1923. Serial No. 624,803.

To all whom it may concern:

Be it known that I, ERWIN JOSEPHY, a citizen of the United States, and resident of New York, in the county of New York 5 and State of New York, have invented certain new and useful Improvements in Combined Menu Cards and Bills, of which the following is a specification.

The present invention relates to menu 10 cards, having reference particularly to an improved combined menu card, order form and bill adapted for use in registering orders for service of meals in public places such as restaurants, hotel dining rooms, 15 dining cars of railway trains and various other places where meals are served to a considerable number of patrons.

The device is especially adapted for use in conjunction with the sheet holding device 20 set forth, and claimed in my co-pending application Serial No. 465,385 filed April 29, 1921, of which the present application is a divisional application.

When ordering a meal from a waiter 25 under systems now in vogue, a common menu card is provided for use of all patrons, and orders for meals are either orally transmitted to the waiter or written on a separate slip and passed to him for execution. Under 30 this system mistakes are frequently made, disputes between patrons and waiters arise and patrons are liable to be subjected to considerable inconvenience.

My invention has for its principal object 35 the provision of means whereby such liability of mistakes and resultant disputes are obviated.

A further object of the invention is to 40 provide means for facilitating the process of registering and placing an order.

Still further objects of the invention being 45 the provision of means whereby patrons may verify their orders, when the bill is presented for collection by the waiter, and means for recording transactions between 50 patrons and waiters whereby the management of the establishment may be constantly informed as to income and the number and variety of food items disposed of, such data materially assisting their calculations for 55 the purpose of maintaining a well balanced food supply and facilitating bookkeeping.

These and other objects are attained by employing individual printed sheets for use 55 of each patron constituting respectively, a

combined menu card, order form and bill, as hereinafter fully described and specifically set forth in the appended claims.

In the accompanying drawings forming part of this specification, Figure 1 is a face 60 view illustrating an example of my improved menu and bill; and

Fig. 2 is a similar view illustrating a slight modification.

In the drawings, 1 indicates a rectilinear 65 sheet of adaptable paper having across one end an integral tab 2, and across the other end a similar tab 3. These tabs are adapted for engagement beneath spring-clamping devices of the character described in my above 70 named co-pending application, and they contain any suitable indicia adapted for use of the management of the restaurant or other place where the sheet is used as a record of transactions between patrons and waiters, 75 the tab 2, in the example shown, having a space 4 for recording a waiter's number, a space 5 for recording a table number and a space 6 for recording the date of the transaction; and the bottom tab 3 having a 80 marked off space 7 wherein the total amount of the transaction may be permanently recorded.

Across the sheet 1 near the top thereof, is a panel 8 containing printed instructions 85 for patrons, and beneath this panel is a column of horizontally ruled spaces 9 containing a printed list of articles of diet on sale and their prices, each space 9 registering on the left with a blank space 10, for 90 receiving a check mark and on the right with a blank space 11 for containing notations constituting an enumeration of specific charges to be computed in the bill. The sheet is also preferably provided with a plurality of blank spaces 10^a, whereon may be marked extras such as cigars, drinks, etc., the prices thereof being notated in the spaces 11. On the right of the printed list of articles on sale is a column of blank spaces 100 12 whereon may be indicated special directions such as the number of persons to be served, and the quality of the food and the conditions under which it is to be prepared.

In the modification illustrated by Fig. 2 105 of the drawings, the list of food items is divided into courses and placed on parallel panels 13; other slight variations of arrangement of the elements of my improvement adapted to meet requirements of vari- 110

ous food dispensing establishments, may be employed without departing from the spirit of my invention and the scope of the appended claims.

5 In the use of the device, each patron receives from the waiter one of the sheets, and then said patron places, by use of a marking device a suitable check marked, as an X, in each space 10 registering with the food articles desired, whereupon the waiter passes the sheet to the chef for the purpose of having the order filled. If any special directions are necessary the patron notes them on the column 12, and if extras are required, 10 they are marked in the spaces 10a. Upon the completion of the meal the waiter makes notation of the several prices in the spaces 11 and foots up the bill in the bottom space 11a, and hands the sheet to the patron who 15 can readily detect any errors of addition by referring to the printed prices on the sheet. After the bill is collected the sheet is passed in to the cashier who then makes a permanent notation of the total amount of the bill on the space 7, whereupon the sheet is 20 filed away for reference.

Having thus described my invention, what I claim as new and desire to secure by Letters Patent, is:—

25 1. In a combined menu card and bill, a blank having a series of separate spaces containing indicia pertaining to articles which may be ordered, a series of charge figures

adjacent said indicia and registering in a common line therewith, a series of separate spaces each of which registers in a common line with each of the aforesaid indicia, said spaces being appropriately designated to receive an indicator mark against such of said articles as are to be ordered, a secondary series of separate ruled spaces each of which registers in line with one of said indicia and wherein said charge figures may be arranged for totaling and an appropriately designated totaling space arranged below and vertically in alignment with said secondary series of spaces upon said blank.

2. In a combined menu card and bill, a blank provided with a series of article indicia, means for separating said indicia into groups, a series of appropriately designated order mark reception spaces to the left of and adjacent to each of said indicia, a secondary series of outlined item notation spaces to the right of and adjacent to each of said indicia, a series of appropriately designated table, servant, and time indication spaces above said indicia and an appropriately designated space adapted to receive the total charge beneath said indicia and vertically aligned with said item notation spaces.

Signed at New York in the county of New York and State of New York this 17th day of July, A. D. 1922.

ERWIN JOSEPHY.
